WATCHMAN'S ELECTRIC TIME RECORDER.

No. 443,788.

Patented Dec. 30, 1890.

UNITED STATES PATENT OFFICE.

CHARLES E. ONGLEY, OF NEW YORK, N. Y., ASSIGNOR OF ONE-THIRD TO
THOMAS W. ROBERTSON, OF SAME PLACE.

WATCHMAN'S ELECTRIC TIME-RECODER.

SPECIFICATION forming part of Letters Patent No. 443,788, dated December 30, 1890.

Application filed March 17, 1890. Serial No. 344,166. (No model.)

To all whom it may concern:

Be it known that I, CHARLES E. ONGLEY, a citizen of the United States, residing at New York city, in the county of New York and 5 State of New York, have invented a new and useful Improvement in Watchmen's Time-Recorders, of which the following is a specification.

In my application, Serial No. 337,424, filed 10 January 20, 1890, I have shown and described a watchman's time-recorder in which time-printing type-wheels are controlled by a clock-movement and other type-wheels for printing the number of the box, which are electrically controlled from the transmitter, the recorder being also provided with printing mechanism controlled from the transmitter for causing the impressions of the type-wheels on a strip, so that when such impression is made the number of the box and the time of the signal will be simultaneously impressed on the paper in a single line. The transmitter used, preferably, with such recorder is a modification of the common individual signal-transmitter, and is provided with contacts controlling the operation of the number-printing type-wheels of the recorder in succession, and also with a contact controlling the printing mechanism of the recorder, the latter contact being made 15 after the former, so that in the operation of the transmitter the number-printing wheels of the recorder are first set at the right number and then the printing is accomplished, the time-printing type-wheels being constantly set at the right position by the clock-movement.

My present invention constitutes an improvement on the apparatus embodied in the above application, and is illustrated in the 20 accompanying drawings, in which—

Figure 1 is a side elevation of the recorder with the clock-work and front plate removed, as indicated by the line 1 1 of Fig. 3. Fig. 2 is an end view of an entire recorder, looking 25 from the left of Fig. 1. Fig. 3 is a plan of the printing mechanism, paper-feeding mechanism, and clock with that part of the apparatus above the line 3 3 in Fig. 1 removed. Figs. 4 and 5 show details of the feeding 30 mechanism for the time-printing type-wheels.

The transmitter and the circuits intended

to be employed in connection with this recorder are preferably the same as those described in the application above referred to, and are not shown or specifically described 55 herein.

It will be understood that the working parts of the recorder are inclosed in a suitable case and are mounted on a case D, within which are the feeding devices for the record-strip 4. This feeding mechanism is driven, preferably, by a weight suspended on cord 5. The motor is normally held from action by the arm 6 and detent 7, said arm being raised at each movement of the printing-platen 8 60 through the medium of an extension, as will be clear from the drawings. The platen is of sufficient length to span all of the type-wheels, and is preferably composed of a rubber striking-block held in a cup-shaped socket 65 on the end of the printing-lever by its own friction or elasticity only, so that it can readily be removed.

E is the printing-magnet.

The arm 6 is provided with a projecting 70 piece 9, which when the apparatus is at rest bears on one of the lowest portions of the cam-wheel 10, and as soon as the apparatus is released and the weight begins to turn the mechanism a higher portion of the cam comes 75 under said projecting piece and prevents the arm from descending until the cam has made approximately one-third of a revolution, when the projecting piece will pass the point 11 and fall sufficiently to engage with the detent 7 as it comes to the position shown. The wheel 10 is provided with projecting pins 11', which as the cam revolves strike a pivoted 80 lever-carrying at one end a pin p, which extends transversely across the ends of the pawl-arms 31. This movement of the clock-work 85 feeds the paper along into the proper position for printing another record.

Between the record-strip and the type-wheels is the inking-ribbon 12, which is wound 90 from one drum 13 onto another drum 14 by means of the pawl 15, carried by the printing-platen. This feed is accomplished by a step-by-step movement, the drum 14 being advanced one notch for each stroke of the 95 platen, and the length and position of the pawl 15 are preferably so adjusted that it shall

advance the inking-ribbon just before the platen presses the paper and ribbon against the type. When the ribbon has been fed from drum 13 to 14, it can be rewound onto the former by means of the thumb-screw 16, Fig. 2. By this arrangement the paper and the inking-ribbon are independently fed, and a fresh inking-surface is presented for each impression. Preferably four type-wheels are employed, as fully set forth in the above application and as indicated in dotted lines at I I' H H' in Fig. 2 of this specification. The two type-wheels H H' are the time-printing wheels and are periodically moved forward by the time-piece 17 (which is supported on or adjacent to the front plate of the recorder) in the following manner:

On an arbor of the time-piece is a wheel 18, provided with cam-teeth 19, preferably twelve in number. In close proximity to the cam-faces of the teeth is supported an arm 20, having an anti-friction bearing 21, and said arm is rigidly connected to arm 22 through the medium of shaft 23. Connected to one end of 22 is a rod 24, the other end of which is connected to the pivoted lever carrying the weight 25. As the wheel 18 is revolved by the time-piece the teeth 19 in succession move the arm 20 in the direction of the arrow, Fig. 4, and thereby raise the weight 25, and as each tooth passes the end of the arm allows the weight to drop. This occurs at intervals of five minutes. As the weight falls it strikes another pivoted arm 26, thereby forcing the pawl 27 down, engaging it with a lower tooth in the ratchet h', which is fixed to the minute-printing type-wheel H', so that when the weight is again raised the retracting-spring of arm 26 will turn said wheel H' one space, thus bringing a new time-indicating number into printing position. It will be understood that pawl 27 is provided with two pawl-extensions of different lengths, one co-operating with ratchet h' and the other co-operating with the ratchet h, which is fixed to type-wheel H, when the first-mentioned pawl falls into a deep notch in h'; and that this occurs once during each revolution of wheel 18—that is, once an hour. When this occurs, the hour-wheel H is advanced one space. This mechanism is well known, and is not illustrated in detail in this case.

The type-wheels I I', which are designed, primarily, for printing the box or station number, are moved in one direction by the magnets M M', respectively. Each of said magnets is provided with an armature and an armature-lever 28, and depending therefrom a pawl 29, which engages with a ratchet 30, fixed to said type-wheels. The pawl-lever is extended, as shown at 31, for a purpose which will be hereinafter described.

32 is a detent to prevent retrograde motion of the type-wheel I', and it will be understood that there is a similar detent for wheel I.

In detents 32 are placed pins 32', extending across the arms of pawls 29, so that when the

latter are retracted they carry with them the detents 32.

33 is a stop to prevent the time type-wheels 70 from moving more than a single space at each impulse. This detent is connected to 26 by a link, so that the two parts move together.

Wound onto pulleys fixed to type-wheels I I', respectively, are two cords 34, attached to weights 35, which slide in tubes 36. These tubes are provided with small perforations near the ends and serve as dash-pots to retard the motion of the weight therein in the well-known manner. I have shown the tubes 80 as held in place by screws 37.

The operation of the apparatus will now be described. The first effect of the transmitter is to vary the line including magnet M a certain number of times, bringing the type-wheel I to the proper point to designate the first figure of the box or station number. The second effect is to vary the line including magnet M' a certain number of times, thus bringing type-wheel I' to the proper position 90 to indicate the second figure of the box-number. The next effect of the transmitter is to change the condition of the line including printing-magnet E, thus moving the printing-platen against the type-wheels and printing 95 at one stroke and in a single line the box-number set up as above described and the time at which the box-number was sent in by means of the time type-wheels H H', as heretofore set forth. This same motion of the 100 platen moves the inking-ribbon a short distance. It also raises arm 6 and allows the weight to act to advance the paper and to trip the type-wheel detents through the medium of the projecting pins 11' and the 105 pivoted arm against which these pins bear as the cam revolves. As soon as said detents are tripped the weights 35 descend, thus returning the number-printing type-wheels to their zero position.

In my application hereinbefore referred to the type-wheels were returned to zero by means of a certain arrangement of springs which were put under tension as the type-wheels were moved into position; but this arrangement has been found somewhat imperfect, owing to the fact that the tension of the spring is irregular—that is, it increases irregularly as the type-wheels are moved forward and it acts with too great intensity 120 and suddenness when released, thus tending to disarrange the apparatus, and especially to carry the type-wheels by their proper position of rest. In the present arrangement the stress on the propelling mechanism for the type-wheels is practically the same at all points, irrespective of the distance through which they are moved, and when released the type-wheels are returned without severe strains on the apparatus, owing to the retard- 125 ing action of the air in the tubes 36.

Having thus described my invention, what I claim is—

1. In a watchman's time-recorder, the com-

bination of type-wheels and mechanism controlled by a transmitter for moving the same to any desired position, independent type-wheels advanced periodically by time mechanism, a platen co-operating with all the type-wheels, a paper-feeding mechanism, and an independent ink-ribbon feed operated by movement of the platen, substantially as described.

10 2. In a watchman's time-recorder, the combination of time-printing type-wheels controlled by time-movement, printing mechanism, an electro-magnet controlling the same, the paper-feed and an ink-ribbon feed also controlled by said electro-magnet, an independent number-printing type wheel or wheels, and a magnet or magnets for controlling the same, substantially as described.

15 3. In a time-recorder, the combination of an adjustable type wheel or wheels, a platen therefor, an ink-ribbon passing between the type-wheel and the platen, said ribbon being wound on two drums, one of which has a ratchet-wheel, and a pawl projecting from the platen-carrying arm into proximity to said ratchet, whereby when the platen is operated the ink-ribbon is moved forward, substantially as described.

20 4. In a recorder, the combination of a type-wheel, a magnet and armature for moving said wheel in one direction, a detent to prevent retrograde movement, means operated by the printing-magnet for releasing said detent, and a weight operatively connected to said type-

35 wheel and sliding in a tube for returning the wheels to zero, substantially as described.

5. In a recorder, the combination of a type-wheel, a magnet and armature for moving said wheel in one direction, and a weight operatively connected to said type-wheel and sliding in a tube for returning the wheel to zero, substantially as described.

40 6. In a recorder, the combination of a type-wheel, means for propelling said wheel in one direction, a detent to prevent retrograde movement, means for tripping the detent, and a retarded weight operatively connected to said type-wheel for returning it to zero, substantially as described.

45 7. In a recorder, the combination of a type-wheel, means for propelling said wheel in one direction, and a retarded weight operatively connected to the type-wheel for returning it to zero, substantially as described.

55 8. In a recorder, the combination of type-wheels, means for propelling each wheel in

one direction, a detent to prevent retrograde movement, means for tripping the detent, and a cord connected to the type-wheel shaft and to a weight sliding loosely in a dash-pot for returning the wheels to zero, substantially as described.

9. In a recorder, the combination of one or more type-wheels, means for propelling each wheel in one direction, means for returning the wheels to zero, a detent to prevent retrograde movement of the wheels, and a trip for the detent, consisting of a pivoted lever, one end of which is adjacent to the propelling and detent pawls, the other end of which is adjacent to a movable part of the paper-feeding train, substantially as described.

10. In a recorder, the combination of type-wheels and means for returning them to zero, a detent for the clock-work, moved by the armature of the printing-magnet, a cam-wheel moved by said clock-work beneath the detent to hold it elevated during a definite period, and projections for tripping the type-wheel detents, substantially as described.

11. In a watchman's time-recorder, the combination of time-printing type-wheels, a time mechanism mounted on or adjacent to the register-frame, but entirely outside of the same, a wheel with cam-teeth driven by said time mechanism, an arm with a bearing co-operating with said cam-teeth and connected by levers to a weight, and propelling-pawls for the time-printing type-wheels, operated by the weight, substantially as described.

12. In a recorder, the combination of several type-wheels in line with each other and independently movable, a part of said wheels being controlled by a transmitter and a part of said wheels being controlled by time mechanism, and a platen common to all of said type-wheels and consisting of an elastic striking-block loosely held in a socket, substantially as described.

13. A printing-platen comprising, in combination, a cup-shaped socket and an elastic striking-block held in said socket by its own friction or elasticity only, whereby the block can be readily removed and replaced, substantially as described.

This specification signed and witnessed this 15th day of March, 1890.

CHARLES E. ONGLEY.

Corrections in Letters Patent No. 443,788.

It is hereby certified that in Letters Patent No. 443,788, granted December 30, 1890, upon the application of Charles E. Ongley, of New York, N. Y., for an improvement in "Watchmen's Electric Time-Recorders," errors appear requiring the following corrections, viz.: In line 7 of the grant and in the printed head of the specification, it is stated said Ongley assigned "one-third" to Thomas W. Robertson, whereas it should have been stated that he assigned *one-half*; and that the said Letters Patent should be read with these corrections therein that the same may conform to the record of the case in the Patent Office.

Signed, countersigned, and sealed this 24th day of March, A. D. 1891.
